FRANK L. WEST AND CONRAD J. KORTZ, OF CLEVELAND, OHIO.

WIRE-HOOK BILL-FILE.

Mc. 823,654.

Specification of Letters Patent

Patented June 19, 1906.

Application filed February 13, 1906. Serial No. 300,842.

To all whom it may concern:

Be it known that we, FRANK L. WEST and CONRAD J. KORTZ, citizens of the United States, residing at Cleveland, in the county 5 of Cuyahoga and State of Ohio, have invented certain new and useful Improvements in Wire-Hook Bill-Files; and we do declare that the following is a full, clear, and exact description of the invention, which will enable others skilled in the art to which it 10 pertains to make and use the same.

Our invention relates to wire-hook bill-files; and the invention consists in the construction and combination of parts, substantially as shown and described, and particularly pointed out in the claims.

In the accompanying drawings, Figure 1 is a rear view of the invention complete, showing an outline of the cardboard or placard, 20 the metallic plate thereon, and the hook connected therewith, as hereinafter more fully described. Fig. 2 is an edge elevation, and Fig. 3 is a vertical sectional elevation, of the invention. Fig. 4 is a bottom edge view of Fig. 1, and Fig. 5 is a cross-section on line *xx*, Fig. 1. Fig. 6 is a rear perspective view of the disk or engaging plate.

Inasmuch as devices of this kind are used mostly as advertising novelties, they should 30 be comparatively inexpensive in manufacture as well as possessed of such utility and simplicity as will recommend them to the public. Hence our invention is made with three parts only—a cardboard or placard A, 35 also referred to as a "flexible board," a wire hook B, and an engaging and locking plate C for fixing the hook operatively upon said cardboard or board A. As to the said part A, it usually is made of a suitably stiff card- 40 board, pasteboard, or the like and provided with an eyelet or hole *a* for hanging it upon the wall; but it may be made of any other suitable material, such as wood or metal.

The hook B has a hook portion 2 and a 45 stem or shank 3, engaged beneath or in a depression, groove, or channel 4, struck up in plate C, and said plate has flexible ears or lugs *c* integral with its edge oppositely, which are projected through suitable slits or holes 50 in board A and bent at right angles on the face thereof, so as to hold said plate permanently and firmly on said board. In this way the metal plate C is fastened to the back or board A without the use of any added

means, and the cost of construction is kept to 55 the minimum possible in this particular.

Respecting hook B, two things especially are desirable—that it should pack flat against the cardboard at all points for shipping and that it should be firmly locked in using position, Fig. 3, both as against being pulled out and against rocking or rotating when in said position. To these ends I provide the stem 3 of the hook between its ends with a substantially right-angled shoulder bend or projection 5, forming both a locking-catch against pulling the hook out of its engagements and against lateral rocking thereof, and in this connection as a further and important feature of the invention I form an open-walled 60 slot 6 in the back of channel 4, between the ends thereof and approximately one-third the length of said channel. The material at the sides of said slot is thrown out into parallel walls 7, and the mouth to said channel 70 is bent outwardly, forming a flaring lip 8 to facilitate the introduction or entrance of the approximately right-angled shoulder 5 of stem 3 into channel 4 and into its working 75 place between walls 7, where it also rests 80 against end 9 of slot 6 and can go no farther. The walls 7 stand up so rigidly that they confine hook 2 to its open right-angled position for use, and there is no lateral looseness or play thereof whatever. It will be observed 85 that this locking of the hook C as to both these movements is confined wholly to plate C and its own struck-up side walls 7 in combination with the stem of the hook, which is so constructed as to be engaged laterally by 90 said walls and to stop sharp against the end 9 of slot 6. In this connection it is also to be further observed that the board A is flexible 95 and can be bent or flexed away from plate C more or less, as may be found desirable, when it comes to drawing the hook down to pass locking-shoulder 5 into channel 4 through or beneath lip 8. This appears in Fig. 2, where board A is bent away from plate C, and the said shoulder 5 is shown as in or beneath lip 8, from which a further pull of the hook will bring said shoulder into slot 6 between walls 7, and board A will flex back again. Having 100 the plate C engaged with board A at its sides facilitates this operation.

From shoulder 5 back the stem has an inclined portion 10, which forms the back of said shoulder or projection.

The channel or groove 4 is practically as deep as the stem of the hook, and the hook proper, 2, and bend 5, forming said shoulder, lie in the same plane, so that when the parts 5 are fixed for shipping both hook and bend 5 will lie flat against opposite sides of board A, Figs. 1 and 4, and prevent any possible injury to the board A by reason of injurious projections here or there.

10 It will be further noticed that stem 3 has a single stop-shoulder 5 and that the end of said stem above said shoulder is inclined from the point of said shoulder back into axial alinement with the said stem. Hence when 15 the hook is in use, Fig. 3, shoulder 5 engages in substantially hook fashion on stop 9 at the bottom of slot 6. The flare 8 at the upper end of channel or groove 4, in conjunction with the flexible board or plate A, enables 20 shoulder 5 on stem 3 to pass into the top flared portion of channel 4, and the flexing or bending of part A is necessary even with flare 8, because there must be inward accommodation for upper inwardly-inclined projection 25 10, as illustrated in Fig. 2.

What we claim is—

1. A new article of manufacture, consisting of a flexible board, a bill-hook having a stem with a single right-angled bend between 30 its ends and its upper extremity inclined inwardly from said bend, and a sheet-metal plate fixed to the back of said board and having an inside channel for said stem from top to bottom provided with an open slot between its ends, the said slot having outwardly-projecting parallel side walls from end to end 35

adapted to bear laterally against the bend in said stem and hold the hook firmly in working position.

2. In bill-files, a flexible board, a metallic 40 plate having ears integral therewith oppositely at its edge engaged through said board and locked thereon and provided with a vertical channel inside midway between said ears, said channel having an open slot with 45 outwardly-projecting parallel walls at its sides, in combination with a bill-hook in said channel having a single right-angled bend adapted to be engaged on its sides by said walls to prevent lateral play of said hook, and 50 the said bend forming a shoulder adapted to seat upon the lower edge of said slot.

3. A bill-file having a flexible board, a sheet-metal plate fixed to said board at its edge and provided with a struck-up channel 55 having an open-walled slot between its ends and an outwardly-flared lip at the entrance to said channel, in combination with a bill-hook having a single right-angled bend in its stem adapted to be drawn into said walled 60 slot beneath said flared lip, and the upper portion of said stem inclined from said bend inward substantially into alinement with the body of the stem.

In testimony whereof we sign this specification in the presence of two witnesses.

FRANK L. WEST.
CONRAD J. KORTZ.
